UNITED STATES PATENT OFFICE

JOE BROWN, OF GRANITE CITY, ILLINOIS

DESIGN FOR A STOVE OR RANGE

Application filed August 17, 1931. Serial No. 40,871. Term of patent 14 years.

To all whom it may concern:

Be it known that I, JOE BROWN, a citizen of the United States, residing at Granite City, county of Madison, State of Illinois, have invented a certain new, original and ornamental Design for a Stove or Range, of which the following is a specification, reference being made to the accompanying drawing forming a part thereof, in which the figure is a perspective view of a stove or range embodying my new design.

I claim:

The ornamental design for a stove or range substantially as shown.

JOE BROWN.
